UNITED STATES PATENT OFFICE.

WILLIAM S. SCHWARTZ, OF PERRYDALE, OREGON.

HOG-TRAP.

SPECIFICATION forming part of Letters Patent No. 791,219, dated May 30, 1905.

Application filed February 15, 1905. Serial No. 245,754.

To all whom it may concern:

Be it known that I, WILLIAM S. SCHWARTZ, a citizen of the United States, residing at Perrydale, in the county of Polk and State of Oregon, have invented certain new and useful Improvements in Hog-Traps; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in hog-traps; and the object of the invention is to produce a simple and efficient apparatus of this nature in which a hog may be driven and securely held while being ringed or held upon its side; and the invention consists, further, in various details of construction and in combinations and arrangements of parts, which will be hereinafter fully described and then specifically defined in the appended claims.

My invention is illustrated in the accompanying drawings, which, with the letters of reference marked thereon, form a part of this application, and in which drawings similar letters of reference indicate like parts in the views, in which—

Figure 1 is a perspective view of my improved hog-trap, showing one end open, whereby access may be had to the head of the animal. Fig. 2 is a front elevation looking into the trap with the front gate swung open, a portion of the apparatus being shown in section. Fig. 3 is an end elevation of the rear of the trap. Fig. 4 is a perspective view of the apparatus, showing the same let down for the purpose of holding an animal upon its side. Fig. 5 is a perspective view showing one of the fastening devices at the end of the apparatus, and Fig. 6 is an enlarged detail perspective view showing the manner of holding one end of the swinging lever.

Reference now being had to the details of the drawings by letter, A designates a boxing or crating having a flooring A' and one fixed side A². The rear of the frame has a tilting gate B, with a lever B' projecting above the

pivotal point B², forming a handle whereby said gate may be tilted upon said pivot. The lower end of said gate is adapted to swing into a recess intermediate the cross-pieces B³, (shown clearly in Figs. 1 and 4 of the drawings,) whereby the gate may be securely held closed against a pressure coming against the same lengthwise of the apparatus. 55

C designates a hinged top having a ring C' fitted to a cross-piece C², fastened to the swinging end of said top, said ring being adapted to fit over the handle B', as shown in Fig. 4 of the drawings, when it is desired to hold the gate in the position shown in said figure. The ends of the cross-piece C² project beyond the longitudinal strips of the door and are adapted to support the free end of said door. 60

The side D of the apparatus is mounted upon hinges D', and to the upper longitudinal strips of said side D are hinged the folding supporting-legs D², which are utilized to support said folding side in a horizontal position, as shown in Fig. 4, when said side is lowered in the position shown for the purpose of holding an animal upon its side. When the folding side is raised to an upright position, as shown in Figs. 1 to 3, inclusive, said legs D² fold between the longitudinal strips of the side, as will be readily understood. Secured 70

to said folding side is a stanchion E, to the lower portion of which are fastened the hooks E', (shown in Fig. 2 of the drawings,) which are adapted to be engaged by an eyebar E², which is fastened to the swinging lever F. 75 It will be observed that said lever F has a concaved portion F' upon one edge thereof corresponding to the concaved portion F², formed upon the inner edge of one side of said stanchion. Fixed to the upper edge of 80 the stanchion is a rack-bar F³, which is designed to be engaged by a pawl G, pivotally mounted at G' upon said lever F. A spring G² is fastened at one end to the handle end of said lever and also to said pawl in the 85 manner shown in Fig. 2 of the drawings, whereby one end of the pawl will be normally held in engagement with the teeth of said rack-bar. 90

H designates a door which is hinged at an 95

inclination to the forward end of the trap, and straps H' , having hooks H^2 , are carried by the swinging side, whereby the front gate or door may be held closed.

5 The lever F , it will be observed, is guided in its swinging movements in a space intermediate the cross-pieces K and K' , forming the top of said stanchion.

Referring to Fig. 4 of the drawings, it will 10 be seen that the swinging side has a bail N fastened to the cross-pieces forming said side, and N' designates a hook fastened to a strap O , the other end of said strap adapted to be fastened to a fixed bail Q , also secured to the 15 swinging side, the purpose of said strap being to securely grasp and hold the animal to the side as it swings down with the stanchion.

The operation of my apparatus is simple and is as follows: When it is desired to secure an 20 animal within the trap, the swinging gate at the rear thereof is swung open to allow the animal to enter head foremost. As the head of the animal passes within the stanchion, the lever F is swung laterally, so that the concaved 25 portions F' and F^2 will securely hold the animal in place, after which the gate H may be opened and access may be had to the head of the animal. When it is desired to throw the animal into a recumbent position upon its side, 30 the door C may be raised and held open, as shown in Fig. 4 of the drawings, and the strap O may be adjusted about the animal, securely holding the same to the folding side before the latter is swung down into the position shown in Fig. 4.

While I have shown a particular form of apparatus illustrating my invention, it will be understood that I may vary the details of the same, if desired, without in any way departing from the spirit of the invention.

40

Having thus fully described my invention, what I claim as new, and desire to secure by Letters Patent, is—

1. A hog-trap having a pivotal gate at the rear end thereof, a portion of said gate extended to form a handle, a hinged door forming the top of the trap, a ring carried by said top and adapted to engage over said handle portion of the gate, when the top and handle are raised to vertical positions, a stanchion, a lever adjustably held upon said stanchion, and a rack-bar, a pawl carried by said lever and adapted to engage the teeth of said rack-bar, as set forth.

45 2. A hog-trap having a pivotal gate at the rear end thereof, a stanchion, a lever, series of hooks carried by said stanchion, an eyebar fastened to said lever and adapted to engage said hooks, a rack-bar upon the stanchion, a spring-pressed pawl pivotally connected to 50 said lever and adapted to engage said rack-bar, and a pivotal door at the front of the trap, as set forth.

55 In testimony whereof I hereunto affix my signature in presence of two witnesses.

WILLIAM S. SCHWARTZ.
